UNITED STATES PATENT OFFICE.

ALBERT R. LELAND, REUBEN B. BENJAMIN, AND GEORGE A. SELLAR, OF CHICAGO,
ILLINOIS, ASSIGNORS TO BENJAMIN-SELLAR MANUFACTURING COMPANY, OF
CHICAGO, ILLINOIS, A CORPORATION OF ILLINOIS.

TOY MOLD.

1,330,197.

Specification of Letters Patent. Patented Feb. 10, 1920.

Original application filed January 8, 1916, Serial No. 70,994. Divided and this application filed November 11, 1918. Serial No. 282,072.

To all whom it may concern:

Be it known that we, ALBERT R. LELAND, REUBEN B. BENJAMIN, and GEORGE A. SELLAR, all citizens of the United States, residing at Chicago, in the county of Cook and State of Illinois, have jointly invented certain new and useful Improvements in Toy Molds, of which the following is a full, clear, concise, and exact description, reference being had to the accompanying drawings, forming a part of this specification.

Our invention relates to toy molds for building blocks—that is, to molds which are to be sold as toys to be used by children in making toy building blocks so that the children themselves may make the desired number of the various shaped blocks.

One of the objects of our invention is to provide such molds which will be simple in construction, convenient to use, and durable and cheap to manufacture.

Further objects will appear from the detailed description to follow taken in connection with the appended claims.

In the drawings, in which we have shown several embodiments of our invention—

Figure 1 is a perspective view of two L-shaped sheet-metal members forming the sides of the mold;

Fig. 2 is a perspective view of a sheet-metal member forming the bottom of the mold;

Fig. 3 is a vertical longitudinal section through the bottom member of the mold;

Fig. 4 is a vertical longitudinal section, similar to Fig. 3, of another form of bottom for the mold;

Fig. 5 is a plan view of another form of mold; and

Fig. 6 is a section on the line 6—6 of Fig. 5 of the bottom of the mold.

Referring now to the drawings in detail, and first to the form shown in Figs. 1, 2, and 3, the mold here shown comprises a dished or trough-like member 10 which may be formed of sheet-metal and which is dished deeply enough to receive the L-shaped side-wall members 11 and prevent their spreading when they are inserted in place in the bottom member 10.

The L-shaped members are proportioned so as to fit snugly in the dished portion 12

of the trough-like member 10, the lower edges 13 of the side members 11 resting on the bottom of the dished member 10. The 55 edge 14 of the shorter side of the L-shaped member fits against the inside face of the longer side 15 of the other L-shaped member when the L-shaped members are inserted in position in the dished member 10. 60

The use of the mold is obvious. The child places the two L-shaped members 11 in the dished member 10 and fills the mold with the moldable material and then removes the mold from the molded material. 65 This may be done by turning the mold upside down on a flat surface and lifting off the dished member 10 and then drawing away the side members 11.

In Fig. 4 is shown a modification of the 70 bottom member of the mold, in which the dished base 15¹ is provided with a peripheral rectangular groove or channel 16 at the bottom, to receive the lower edges of the L-shaped side-wall members. In this form, 75 also, the bottom member may be of formed sheet-metal.

In the form shown in Figs. 5 and 6 the base or bottom member 17 may be of cast metal and is provided with a deep narrow 80 rectangular groove 17¹ to receive the two L-shaped side members 11, which may be of sheet-metal. In this construction the groove 17¹ is deep enough to hold the side members 11 in position and to prevent their spreading. 85

This application is a division of our co-pending application Serial No. 70,994, filed January 8, 1916—toy molds.

We claim as new and desire to secure by 90 Letters Patent of the United States:

1. In a toy mold for toy building blocks, two L-shaped sheet-metal members together forming a rectangular inclosure, and a trough-shaped sheet-metal bottom plate for 95 supporting said L-shaped members, the sides of said trough-shaped bottom plate extending upwardly alongside and engaging said L-shaped members to hold them in proper relative position and to keep them from 100 spreading, the sides of said trough-shaped bottom plate serving as the sole means for preventing the L-shaped members from separating and spreading.

2. In a toy mold for toy building blocks, two L-shaped sheet-metal members together forming a rectangular inclosure, and a bottom member for supporting said L-shaped members having a depression to receive the lower edges of said L-shaped member, said depression being deep enough to support said L-shaped members in proper relative position and to prevent them from spreading, the sides of said depression being the sole means for preventing said L-shaped members from separating and spreading.
3. In a toy mold for toy building blocks, two L-shaped sheet-metal members together forming a rectangular inclosure, and a trough-shaped sheet-metal bottom plate for supporting said L-shaped members, the sides of said trough-shaped plate extending upwardly alongside and engaging said L-shaped members to hold them in proper relative position and to keep them from spreading, said bottom plate being provided

with a rectangular channel to receive the lower edges of said L-shaped members.

4. In a toy mold for toy building blocks, two L-shaped sheet-metal members together forming a rectangular inclosure, and a trough-shaped sheet-metal bottom plate for supporting said L-shaped members, the sides of said trough extending upwardly along- side and engaging said L-shaped members to hold them in proper relative position and to prevent them from spreading, said bottom plate being also provided with a peripheral laterally-extending flange.

In witness whereof, we have hereunto sub- scribed our names.

ALBERT R. LELAND.
REUBEN B. BENJAMIN.
GEORGE A. SELLAR.

Witnesses to Geo. A. Sellar:

HARVEY J. BAVERSTOCK,
CHARLES PACK.
